UNITED STATES PATENT OFFICE

HANS TIMM, OF RISSEN, NEAR HAMBURG, GERMANY

SUPPORT FOR MENUS OR BILLS-OF-FARE

Application filed October 1, 1927. Serial No. 223,358.

This invention relates to an improvement in supports for menus or bills-of-fare, and its object is to provide suitable means thereon for safely clamping the menu thereto and allowing a quick removal of the same therefrom.

The accompanying drawing illustrates the improved arrangement: Fig. 1 is a front view of the support with the menu thereon, Figs. 2 and 3 are vertical sections therethrough with the parts in their position of use and respectively in their detached position, Fig. 4 is a front view of a detail thereof, and Fig. 5 is a plan view of the latter.

15 The support 1 has a flat T-shaped upper member 2 in which screw-threaded holes are provided for the reception of small screws 3 having each a counter-nut 4 at one end and an integral head 5 at the other end.

20 The menu or bill-of-fare 8, preferably within a celluloid envelope of known kind, is at its lower end provided with holes 9 of sufficient width to pass them over the screw-heads 5.

25 Furthermore, a covering strip 6, preferably of springy material, is provided with bayonet holes 7 having lower wide apertures adapted to be passed over the screw-heads 5 and upper narrow apertures fitting over the screws 3.

30 To use the support, first, the screws 3 are adjusted to their required position thereon, that is so that the distance between the inner ends of the screw-heads 5 and the upper member 2 of the support suits about the thickness 35 of the menu 8 and of the strip 6. Then, the menu 8 is passed with its holes 9 over the screw-heads 5 and screws 3 until it bears against the upper member 2 of the support.

Finally, the strip 6 is also passed with the 40 lower wide apertures of its bayonet holes 7 over the screw-heads 5 and then depressed until the upper narrow apertures of its bayonet holes 7 fit over the screws 3 and the strip 6 is thus located between the screw-heads 5 and the lower end of the menu 8. The use

of a strip 6 of springy material is preferred for its being tightly pressed in its holding position. The removal of the menu takes place in the same way, but vice versa.

50 What I claim, is:—

A support for menus or bills-of-fare, comprising in combination with the foot support proper, a horizontal bar on said support, screws adjustably mounted on said horizontal bar and having each a head projecting somewhat from said horizontal bar, a clamping bar, an envelope of celluloid having inwardly set off edges on the upper side and on the two long sides, so that the front and rear sides of said envelope are rendered resilient, 55 the open lower side through which the bill-of-fare is to be inserted being clamped by means of the clamping bar behind said screw heads.

60 In testimony whereof I have hereunto set my hand.

65 HANS TIMM.
